UNITED STATES PATENT OFFICE

150,477

DESIGN FOR A PICTURE FRAME

Angelo Tumminello, Chicago, Ill.

Application October 28, 1946, Serial No. 134,333

Term of patent 3½ years

(Cl. D29—20)

To all whom it may concern:

Be it known that I, Angelo Tumminello, a citizen of the United States, residing at Chicago, in the county of Cook and State of Illinois, have invented a new, original, and ornamental Design for Picture Frames, of which the following is a specification, reference being had to the accompanying drawing, forming part thereof.

Fig. 1 is a perspective view of a picture frame showing my new design, and Fig. 2 is a medial cross-section thereof.

I claim:

The ornamental design for a picture frame, as shown.

ANGELO TUMMINELLO.
